(57) **CLAIM**

We claim the ornamental design for a container with heat seal, as shown and described.

DESCRIPTION

FIG. 1 is a front perspective view of a container with heat seal embodying the design of the present invention.

FIG. 2 is a perspective view of the container with heat seal of FIG. 1;

FIG. 3 is a front elevational view of the container with heat seal of FIG. 1;

FIG. 4 is a top elevational view of the container with heat seal of FIG. 1;

FIG. 5 is a bottom elevational view of the container with heat seal of FIG. 1;

FIG. 6 is a left side elevational view of the container with heat seal of FIG. 1; and

FIG. 7 is a right side elevational view of the container with heat seal of FIG. 1.

FIG. 8 is a front perspective view of the container with heat seal of FIG. 1 with the sides in a different position.

FIG. 9 is a perspective view of the container with heat seal of FIG. 8;

FIG. 10 is a front elevational view of the container with heat seal of FIG. 8;

FIG. 11 is a top elevational view of the container with heat seal of FIG. 8;

FIG. 12 is a bottom elevational view of the container with heat seal of FIG. 8;

FIG. 13 is a left side elevational view of the container with heat seal of FIG. 8; and,

FIG. 14 is a right side elevational view of the container with heat seal of FIG. 8.
